UNITED STATES PATENT OFFICE.

DAVID McCRRORIE SHANNON, OF BIRKENHEAD, ENGLAND.

INTERNAL-COMBUSTION ENGINE.

Application filed January 31, 1922, Serial No. 533,132, and in Great Britain February 3, 1921.

This invention relates to internal combustion engines, and has reference more particularly to apparatus for the injection of liquid fuel in internal combustion engines 5 of the type in which the fuel is injected by means of a blast of air or other gas obtained from the working cylinder of the engine; and the object of the invention is to provide apparatus for this purpose which shall 10 be free from the objections which have heretofore obtained, and by the use of which the necessity for providing the usual compressor driven by the engine and in which comparatively low pressure air is raised to 15 the injection pressure, is obviated.

Hereto the attempts to take air or gases from the engine cylinder after compression therein, and further compressing such air or gases to the injection pressure by means of 20 a separate compressor have not been successful because the compressor, designed to give the final pressure, has had to deal with gases of such high initial temperature as to make successful lubrication impossible, 25 thus rendering the working of the compressor piston and valves uncertain, and their working life of comparatively short duration.

According to the present invention, the 30 gases taken, at the appropriate part of the cycle, from the working cylinder of the engine, are discharged therefrom through a cooling device interposed between the working cylinder and a comparatively small compressor used to give the final compression; this cooling device comprises fluid cooled 35 heat exchanging surfaces, say one or more comparatively long small-bore tubes so arranged that the gases pass therethrough in a thin stream or streams to give efficient 40 cooling and to prevent the passage through the cooler to the compressor, of any flame or high temperature gases which would cause an explosion in the compressor, the comparatively 45 large extent and long length of the heat exchanging surfaces of the cooler in proportion to the small cross-sectional 50 area of the passage-ways for the gases thus ensuring immunity from explosion in the compressor, and maintaining a reasonably low temperature in the latter.

Apparatus constructed according to the invention comprises,—a cooler to cool the comparatively high temperature air or 55 other gases withdrawn from the working cylinder and before delivery thereof to the

compressor; a compressor for raising the pressure of the said air or gases to a suitable valve for injecting the fuel; a fuel supply pump; and a pulverizing chamber in 60 which the air or other gas, after said final compression, is thoroughly mixed with fuel supplied to the said chamber, which chamber is fitted with a nozzle or flame plate through which the fuel sprayed by the compressed gases is injected into the working 65 cylinder of the engine.

Preferably the same nozzle is used for the passage of the air or other gas from the working cylinder to the compressor cylinder, and for spraying the fuel into the working cylinder, thus dispensing with the usual cam operated inwardly or outwardly opening valve.

Alternatively, the air or other gas may be 75 taken from the cylinder by way of a separate opening, through the cooler, a non-return valve being located at the end of the cooler remote from the working cylinder. The fuel may be introduced into the mixing 80 chamber at any desired point in the stroke, and on the forward movement of the compressor piston; is carried with the air into the working cylinder or the fuel may be injected into the air stream by a fuel supply 85 pump the plunger of which has a movement similar to and synchronous with that which operates the compressor piston.

The compressor may be integral with the cooler or be separate from it, as may be 90 most convenient, and may be driven in any suitable manner by levers, fluid pressure, or gearing from the engine.

The invention is applicable generally to 95 internal combustion engines the fuel of which is sprayed into the working cylinders, and is particularly applicable to engines of this type having opposed pistons, say of the now well known Fullagar type, and the invention will, in the first instance, be described as applied to a Fullagar 100 engine.

In the preferred form, the cooler casing may be cylindrical and may be arranged co-axially with the fuel injection nozzle which 105 in the Fullagar engine passes through the central zone of the cylinder liner, the cooler extending across the water jacket casing of the cylinder, in which case the compressor may be conveniently arranged as a co-axial 110 extension of the cooler.

At the cylinder end the interiors of the

tubular cooling surfaces (which may be straight or curved small bore tubes the exteriors of which are cooled by a suitable cooling fluid circulated through the cooler,) 5 open into a pulverizing chamber leading to the injection nozzle, and at the opposite end they open into the compressor cylinder. Fuel is led to the pulverizing chamber through a fuel inlet nozzle which is preferably centrally located and is provided with jets so disposed that when the compressor 10 makes its working stroke and the gases are forced through the several cooling tubes across the pulverizing chamber, the fuel issuing from these jets is directed across the streams of gas so that the fuel and gases are thoroughly mixed in the pulverizing chamber preparatory to being sprayed into the cylinder through the fuel injection nozzle. 15 The cooler may consist of one or more small bore tubes arranged in the water jacket space of the main cylinder, thus dispensing with a special cooling jacket round the tubes, or it may consist of a bent or 20 straight tube or tubes, each tube being inside another tube of larger bore with the water circulating in its annular space between the two tubes, the length of the tubes being sufficient to bring about the desired 25 amount of cooling.

The action of the apparatus is as follows:

As the air or gas is compressed, during the compression stroke, in the working cylinder, a portion of its passes through the tubular 30 cooling surfaces of the cooler into the compressor cylinder, the piston of which is then forced to the end of its outstroke. At an appropriate period in the cycle, the compressor piston is forced to the inner end of 35 its stroke, compressing the air or gas before it and discharging the said gas through the cooler into the pulverizing chamber, where it meets with the fuel then being sprayed from the fuel inlet nozzle and the mixture 40 of fuel and gas is then sprayed into the working cylinder through the injection nozzle. The pump delivering fuel would usually have its movements co-ordinated with that 45 of the compressor piston so that the fuel is delivered to the pulverizing chamber as the compressor piston is making its working 50 stroke.

In a modification, the air or gases passing from the working cylinder to the compressor pass through small bore cooling tubes as described, but additional passage-ways are provided through which the gases pass from the compressor to the pulverizing chamber; the object of providing additional passage- 55 ways for the return flow of the gases is to reduce the resistance as to flow and to reduce the degree of cooling of the gases as they pass through the cooler after final compression.

60 A non-return valve to open on the dis-

charge stroke of the compressor is arranged at any convenient point in the additional passage ways or ways.

In a further modification, instead of small bore tubes to form the heat exchanging surfaces, pairs of concentric tubes may be arranged, the cooling fluid circulating through the inside of the inner tube and around the outside of the outer tube, the air or gas to be cooled flowing through the angular space 75 between the tubes.

In a further modification, a cooler of any suitable type may be fitted to a port in the cylinder liner which is covered by the engine piston when the latter is in its extreme inner position, the cooler leading through a non-return valve to a receiver. When the said port is uncovered by the piston, compressed air or gas is forced through the cooler, cooled 80 therein, and discharged into the said receiver. From the receiver the air or gas is taken to a compressor adapted to raise the pressure to that suitable for injection purposes through a fuel valve and injection nozzle of the ordinary type, the compressor 85 for final compression being separately driven from the engine crank shaft or in any other convenient manner.

Alternatively, the port may be arranged without being covered by the piston, the 90 valve which is located at the end of the cooler remote from the combustion chamber being mechanically or otherwise operated to take the air or gas from the working cylinder when the working pistons are in any 95 desired position.

In the modifications described, it has been assumed that the compressor is of the single piston type, but with the object of relieving the apparatus and the part of the engine structure to which it is attached of all or any 100 part of the loads due to the operation of a single compressor piston, and also with a view to the employment of smaller piston with reduced loads, the compressor cylinder 105 may be fitted with opposed pistons.

The compressor cylinder may be arranged so that the axes of its two bores in which the pistons reciprocate are in the same line, or be offset and parallel, or be inclined at any angle in the same place, or in different planes. Both pistons, or only one of them may be reciprocated, by any suitable means, so as to have a definite relationship to the motion of the main piston or pistons in the working cylinder. Where one piston is reciprocated, the other may be prevented from moving axially by a pin jointed link, or other attachment to some part external 110 to the apparatus.

115 The compressor cylinder is in each case provided with a water jacket.

In a convenient arrangement of the opposed piston type of compressor, the latter 120 may be arranged symmetrically and trans-

versely across the end of the cooler which may be of any suitable type.

The passage-ways traversed by the air or gases from the cooler to the compressor may be fitted with retarders so as to increase the cooling effect, and wire gauze diaphragms may be fitted across the passage-way between the compressor and the pulverizing chamber so as to prevent the passage of flame into the compressor.

As stated, the invention is applicable to internal combustion engines generally and may be employed in such engines using solid pulverized fuel; the parts being modified to suit any particular arrangement.

I have illustrated my invention in the accompanying drawings, in which:—

Fig. 1 is an elevation in conventional medial section and shows the preferred arrangement.

Fig. 2 is a sectional elevation of a modified construction of the cooler; the mode in which the cooler is fitted to the working cylinder, and the mode in which the compressor is operated may be as shown in Fig. 1. Fig. 2^A is a part plan view of Fig. 2.

Figs. 3, 4 and 5 illustrate further modifications of the cooler. Fig. 3 being a view similar to Fig. 2, and being in section on the line III, III of Fig. 4, which is a plan view in section on the line IV, IV of Fig. 3.

Fig. 5 is a plan in section on the line V, V, of Fig. 3.

Fig. 6 is an elevation in section of a further modification in which the cooler heat transmitting surface is located in the water-jacket's space of the working cylinder.

Fig. 7 is an elevation in conventional medial section and shows a modification of the compressor and general arrangement particularly suitable for an opposed piston type of engine such as the well known Fullagar engine.

Referring first to Fig. 1,

A is the working cylinder of an internal combustion engine of say the Fullagar type; a^1 is the water-jacket of the cylinder, a^2 is the fuel inlet opening. B is the nozzle through which the mixture of air and oil is sprayed into the working cylinder. C is the fuel nozzle, through which fuel is sprayed into the atomizing chamber D, E is the cooler, F the compressor and G the oil pump. The cooler which is of cylindrical configuration is arranged with its axis in line with a fuel inlet opening, and the compressor F is arranged in line with the cooler. The cooler consists of a cylindrical casing e^1 which is secured in position in a cylindrical recess in the working cylinder casing, so that the atomizing chamber D is formed between the inner end of the cylindrical casing e^1 and the air and oil nozzle B. The fuel nozzle C is fitted at the end of a cen-

tral passage-way e^2 , from the inlet e^3 of which connection is made to the oil pump G. The heat exchanging surfaces consist of a number of small bore tubes e^4 which traverse the annular space between the cylindrical casing e^1 and the central stalk e^5 in which the central port e^2 is formed. These tubes e^4 open at one end into the atomizing chamber D and open at the other end into the cylinder space of the compressor F.

The cooling water is led from the working cylinder jacket a^1 through the openings a^4 and a^6 into the annular space; it traverses this space and around the tubes e^4 , and flows thence through the connecting passage-way e^7 to the water-jacket f^6 of the compressor, and leaves by the outlet f^7 , or it may enter at f^7 and flow in the reverse direction to that described.

The compressor may be of any suitable type and may be operated in any suitable manner. In the example illustrated f^1 is the piston of the compressor, the rod f^5 of which is connected to a cross-head f^2 , the latter being reciprocated by radius rods f^3 connected to a lever, operated say, by a cam. G is the oil pump, the plunger g^1 of which may be conveniently operated as shown from the cross-head pin f^4 . g^2 is the delivery valve; g^3 the suction valve and g^4 the oil supply pipe.

The compressor is arranged to make its suction stroke just as the period of maximum compression is being reached in the working cylinder; the air or other gas from the working cylinder then passes through the openings b^1 of the air and oil nozzle then passes through the small bore tubes e^4 into the compressor cylinder, being cooled in its passage through the tubes to a temperature which may be as low as that of the atmosphere. The compressor is arranged to make its working stroke at the point in the cycle at which it is desired to introduce oil fuel into the working cylinder, and the pump G makes its working stroke simultaneously; the result is that air from the compressor F is forced through the small bore tubes e^4 into the atomizing chamber D at the same time that the oil is forced through the fuel nozzle C into this chamber; the holes c^1 in the fuel nozzle are arranged to be opposite the ends of the tubes e^4 so that the air or other gas impinges on the jet of fuel, completely atomizing it, the said air and oil being forced by the compressor into the working cylinder through the holes b^1 in the nozzle B.

Referring now to Figs. 2 and 2^A, the arrangement of the cooler is substantially similar to that already described except that the central stalk e^8 is made hollow, the fuel tube e^9 , an annular space e^{10} being formed between the tube e^9 and the bore of the central stalk e^8 . The annular space e^{10} at

one end communicates with the compressor cylinder through the ports e^{11} in the plug e^{12} , the other end of the annular space regarded as a passage-way is controlled by a 5 valve H fitting a seating h^1 on the stalk e^8 .

When the compressor makes its suction stroke the hot gas for the working cylinder passes to the compressor cylinder through the small bore tubes e^4 , being prevented from 10 passing through the annular space e^{10} by the closing of the valve H; when, however, the compressor makes its compression stroke the compressed gas, on being forced to the fuel inlet, passes through the annular space e^{10} as 15 well as through the small bore tubes e^4 . In other respects the construction and action is similar to that already described.

Referring now to Figs. 3 to 5, instead of forming the heat transmitting surfaces of 20 small bore tubes as described, these surfaces are, in this modification formed of concentric tubes e^{13} and e^{14} , so arranged as to form an annular passage-way e^{15} for the gases.

The connection between the compressor 25 and the annular space between the tubes e^{13} and e^{14} is made by passage-way e (see Fig. 4), and the lower end of the said annular space opens into the atomizing chamber D.

The circulating water is led through the 30 space e^{16} round the outer tube and through the space e^{17} within the inner tube, so that the surfaces of these tubes are cooled by the circulating water which enters at the inlet e^{17} , (Fig. 4) thence through the ports e^{18} and 35 e^{19} through the spaces e^{16} and e^{17} , through the ports e^{20} and e^{21} to the outlet e^{22} , and thence to the water jacket of the compressor as already described.

The construction and action of the cooler 40 is similar in other respects to that already described.

Referring now to Fig. 6, the cooler E consists of a small bore spiral tube arranged in the water-jacket space of the working cylinder. The one end of the tube E' is connected by the union h^1 to a port a^3 in the wall of the working cylinder, and the other end is connected by a union h^2 to a fitting O, provided with a non-return valve o^1 and a 45 discharge o^2 leading to a receiver, said receiver being fitted with a compressor adapted to withdraw the compressed air or other gas from the receiver and to deliver it to the fuel inlet of the working cylinder. The said 50 air or other gas and the fuel are simultaneously delivered to the atomizing chamber arranged substantially as described in reference to the atomizing chamber H in the previous figures.

55 Referring now to Fig. 7;—the construction of the cooler E and the fitting of it to the working cylinder A are substantially as described in reference to Fig. 1; the compressor F is, however, arranged with its axis at right angles to the axis of the cooler and in this

modification the compressor is of the opposed-piston type. The air or other gas from the working cylinder is, as the pistons f^9 and f^{10} move out, drawn from the working cylinder through the cooler E, and into the compressor cylinder through the central port f^8 ; when the pistons f^9 and f^{10} approach, the hot air or other gas is driven back through the cooler into the atomizing chamber D where it meets with the oil fuel supplied from the nozzle C, the oil and air or other gas being forced into the working cylinder through the nozzle B.

Both pistons of the compressor may be adapted to be reciprocated as in Fig. 80 7; or one only of them may be reciprocated, the other being held axially fixed by say, linked attachment to the main frame; by this means the compressor cylinder and the means by which it is attached to the working cylinder are relieved from the unbalanced force to which these parts are subjected when the single piston type of compressor is employed.

The arrangement shown in Fig. 7, is particularly suitable for application to engines of the Fullagar type, the pistons f^9 and f^{10} being reciprocated by levers f^{12} , and connecting rods f^{13} having ball and socket attachments to the pistons, the levers f^{12} being reciprocated in any convenient manner, say by the cam surfaces.

A fuel oil pump arranged substantially in the manner described in connection with Fig. 1 is fitted and makes its working stroke 100 simultaneously with the compression stroke of the compressor.

Obviously the inlet e^3 of Fig. 7 may be connected to a fuel pump the plunger of which may in turn be connected to the compressor piston, all of which is of ordinary construction. It will also be obvious that the fitting shown in Fig. 2 may be used with the device of Fig. 7.

Having now particularly described and ascertained the nature of my said invention and in what manner the same is to be performed, I declare that what I claim is:—

1. In an apparatus of the type described the combination of, the working cylinder; fuel injection opening in the wall of the compression space of the said cylinder; a compressor; a conduit through which the compression space of the compressor is always in communication with the said opening, so that the gas partly compressed in the working cylinder passes from the latter to the compressor through the conduit, the said gas after further compression in the compressor passing back through the conduit to the working cylinder; and means for cooling the said conduit; substantially as described.

2. In an apparatus of the type described the combination of, the working cylinder;

a fuel injection opening in the wall of the said cylinder; a water jacket for the working cylinder; means for circulating water through the said jacket; a compressor; a conduit located in a casing communicating with the said jacket through which conduit the compression space of the compressor is always in communication with the said opening, so that the gas partly compressed

10 in the working cylinder passes from the latter to the compressor through the conduit, the said gas after further compression in the compressor passing back through the conduit to the working cylinder; substantially

15 ally as described.

3. In an apparatus of the type described the combination of, the working cylinder; a fuel injection opening in the wall of the compression space of the said cylinder; a compressor; a conduit through which the compression space of the compressor is always in communication with the said opening, through which conduit the gas partly compressed in the working cylinder passes from the latter to the compressor and through which conduit the said gas after further compression in the compressor passes back to the working cylinder; means for cooling the said conduit; a supply of fuel; and a pump for delivering the fuel to the stream of gas passing from the compressor to the working cylinder; substantially as described.

4. In an apparatus of the type described, the combination of a working cylinder; a fuel injection opening in the wall of the said cylinder; a compressor; a conduit connecting the compression space of the compressor to the said opening through which conduit the said space is always in communication with the said opening; a casing connecting the compressor to the working cylinder and enclosing the said conduit; and means for circulating cooling water through the said casing; substantially as described.

5. In an apparatus of the type described, the combination of a working cylinder; a fuel injection nozzle passing through the wall of the said cylinder; a compressor; a conduit connecting the compression space of the compressor to the interior of the fuel injection nozzle through which conduit the said space is always in communication with the interior of the said nozzle; a casing connecting the compressor to the fuel nozzle and enclosing the said conduit; and means for circulating cooling water through the said casing; substantially as described.

6. In an apparatus of the type described, the combination of a working cylinder; a fuel injection nozzle passing through the wall of the working cylinder; a conduit connecting the compression space of the compressor to the bore of the fuel injection nozzle; a casing connecting the compressor

to the fuel nozzle and enclosing the conduit; means for circulating cooling water through the said casing; a central stalk in the casing; a passageway in the central stalk; a fuel spraying nozzle on the end of the said passageway adjacent to the fuel injection nozzle; and a fuel supply connected to the other end of the said passageway; substantially as described.

7. In combination with the elements of claim 6, a fuel supply pump delivering to the said passageway, the plunger of which is connected to the plunger of the compressor so that they make their working strokes together; substantially as described.

8. In apparatus of the type described the combination of, a working cylinder; a water jacket for the said cylinder; an open-ended compartment extending across the water jacket; a fuel injection nozzle located in the said compartment and passing through the wall of the said cylinder; a compressor; a water jacket for the compressor; a casing fitting the said compartment and connecting the compressor to the interior of the fuel injection nozzle; a conduit extending through the casing and connecting the compression space of the compressor to the interior of the fuel injection nozzle; openings connecting the interior of the casing to the water jacket; and a conduit connecting the interior of the casing to the water jacket of the compressor; substantially as described.

9. In combination with the elements claimed in claim 8, a passageway extending through the casing; a fuel spraying nozzle fitted to one end of the said passageway near the fuel inlet nozzle; a fuel pump delivering to the said passageway, the plunger of the pump being connected to the plunger of the compressor so that they make their working strokes together; substantially as described.

10. In apparatus as claimed in claim 3, a second conduit in parallel with the first conduit to intermittently allow passage of gas therethrough and means to close said conduit.

11. In apparatus as claimed in claim 3, connecting the plunger of the fuel pump to the plunger of the compressor so that fuel is delivered to the compressor as the compressor piston is making its working stroke.

12. In apparatus of the type described, the combination of a working cylinder; a fuel injection nozzle passing through the wall of the working cylinder; a compressor having a compression space, a plurality of conduits connecting the compression space of the compressor to the bore of the fuel injection nozzle; a casing connecting the compressor to the fuel injection nozzle and enclosing the said conduits; means for circulating cooling water through the said casing; a central stalk arranged in the said cas-

ing having a flanged end fitting and enclosing the bore of the fuel injection nozzle and through which flange the said conduits pass; a passageway in the central stalk; a fuel supply connected to the inlet end of the said passageway; a fuel spraying nozzle on the outlet end of the said passageway and located in the said enclosed bore of the fuel

injection nozzle so as to form an annular space between the nozzle and the said bore, through which space the gases from the said conduits flow as they pass to the working cylinder; substantially as described.

In witness whereof I set my hand.

DAVID McCRRORIE SHANNON.
